UNITED STATES PATENT OFFICE.

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

CANDELABRUM-SOCKET.

1,215,079

Specification of Letters Patent.

Patented Feb. 6, 1917.

Application filed February 16, 1916. Serial No. 78,680.

To all whom it may concern:

Be it known that I, GEORGE B. THOMAS, a citizen of the United States of America, residing in the city of Bridgeport, county of 5 Fairfield, and State of Connecticut, have invented certain new and useful Improvements in Candelabrum-Sockets, of which the following is a specification.

The present invention relates to candelabrum sockets and particularly to a lining for the socket proper, the object of my invention being to provide a lining for the socket shell which is cheap to make, readily applied and sustained upon the socket without the use of special retaining means.

In the accompanying drawings

Figure 1 is a vertical section through a candelabrum socket in which my invention is embodied;

20 Fig. 2 is a similar view at right angles to Fig. 1.

Fig. 3 is a perspective of same showing the lining partially removed to permit the leading-in wires to be secured to their binding screws.

In sockets of the present type it has been the customary practice to rely upon the insulating character of the candelabrum tube which surrounds the socket shell to afford 30 the necessary insulation which protects the installation from accidental contact with conducting parts. Inasmuch as these candelabrum sockets are ordinarily of porcelain or glass they afford efficient protection to this 35 end. The common candelabrum tubes are thus rather fragile and it has been proposed to substitute therefor metallic or enameled metal tubes for the same purpose. Inasmuch as this introduces a possible element 40 of danger into the installation by reason of the conducting nature of the metal it is necessary to provide an insulator between the shell of the socket and the candelabrum tube to prevent contact between the same.

45 In the embodiment of my invention illustrated, I have shown a socket body 10 comprising the usual insulating button carrying on its lower face an internally threaded thimble 11 which screws upon the upper end 50 of the wire conduit 12 through the holes 13 in which the wires 14 and 15 are led to the binding screw terminals 16 and 17 on the upper surface of the socket body. The center contact 18 is riveted to the wire terminal 55 17 while the shell contact 19 is provided

with the usual base flange 20 which underlies the yoke 21 integral with the base of the wire terminal 16. Surrounding the conduit 12 and socket 10 is a candelabrum tube 22, the upper end of which is somewhat constricted and consequently in danger of accidental contact with the screw shell 19 of the socket. To insulate these parts from each other I provide an insulating casing 23 surrounding the socket shell 19 and in the present form secured thereto by a threaded portion 24 formed between the ends of the casing 23 and adapted to be threaded on the outside of the shell 19. A shoulder 25 formed on the insulating body 10 affords a 70 stop which positions the casing 23 on the shell. In adjusted position the lower end of the casing not only surrounds the shell but it extends below the wire terminals 16 and 17 and insulates the latter as well as 75 preventing the escape of wire beards which might possibly contact with the candelabrum tube.

In order to wire the socket it is only necessary to screw up the casing 23 until the 80 binding screws 16 and 17 have been exposed, whereupon the wires are fastened and the casing screwed down again to inclose the latter. The frictional engagement between the casing and the screw shell 19 is sufficient 85 to prevent the casing from backing off and obviously no other means than the threaded engagement between the parts is required to secure the casing in position on the socket.

I claim as my invention:

1. A candle socket, comprising an insulating body, lamp terminals mounted at one end thereof, means mounted at the opposite end thereof for securing the socket to a wire conduit, wire terminals electrically connected to the lamp terminals and having binding screws arranged at substantially right angles to the longitudinal axis of the socket, an insulating casing carried by one of the lamp terminals and surrounding both the lamp terminals and the wire terminals.

2. A candle socket, comprising an insulating body, screw shell and center contact lamp terminals mounted at one end thereof, means mounted at the opposite end thereof for securing the socket to a wire conduit, wire terminals electrically connected to the lamp terminals and having binding screws arranged at substantially right angles to the longitudinal axis of the socket, an insulat-

ing casing having a threaded area screwed upon the screw shell lamp contact and surrounding both the lamp terminals and the wire terminals.

5. A candelabrum socket comprising an insulating body, wire terminals and a lamp socket screw-shell side contact mounted thereon, an insulating casing threaded on said shell and inclosing said wire terminals 10 and abutting against said body at one end.

15. An electric lamp socket, comprising an insulating body with a peripheral shoulder, wire terminals and a screw shell lamp-receiving contact mounted on said body to one side of said shoulder, in combination with an insulating casing carried by said screw shell and inclosing said wire terminals, said casing abutting at one end against said shoulder on the insulating body.

20. 5. An electric lamp socket, comprising an insulating body with a peripheral shoulder, wire terminals and screw shell lamp-receiving contact mounted on said body to one side of said shoulder, in combination with

an insulating casing having a threaded area 25 externally screwed upon said screw shell and inclosing the wire terminals, said casing abutting at one end against said shoulder on the insulating body.

6. In a candle socket, an insulating body, 20 screw shell and center contact lamp terminals mounted at one end of said body, means at the other end of said body for mounting the same on a support, a peripheral ledge 35 on the side of said body, wire terminals 35 thereon and grooves cutting said edge and leading to said wire terminals, in combination with an insulating casing seated against said ledge and inclosing the lamp terminals and in part the wire grooves. 40

In testimony, whereof I have signed my name to this specification, in the presence of two subscribing witnesses.

GEORGE B. THOMAS.

Witnesses:

G. W. GOODRIDGE,
H. M. WICHERT.

DISCLAIMER.

1,215,079.—*George B. Thomas*, Bridgeport, Conn. CANDLABRUM SOCKET. Patent dated February 6, 1917. Disclaimer filed October 2, 1923, by the assignee, *The Bryant Electric Company*.

Hereby enters this disclaimer—

“To that part of the claims in said specification which are numbered 1 and 2, and which are in the following words, to wit:

“1. A candle socket, comprising an insulating body, lamp terminals mounted at one end thereof, means mounted at the opposite end thereof for securing the socket to a wire conduit, wire terminals electrically connected to the lamp terminals and having binding screws arranged at substantially right angles to the longitudinal axis of the socket, an insulating casing carried by one of the lamp terminals and surrounding both the lamp terminals and the wire terminals.

“2. A candle socket, comprising an insulating body, screw shell and center contact lamp terminals mounted at one end thereof, means mounted at the opposite end thereof for securing the socket to a wire conduit, wire terminals electrically connected to the lamp terminals and having binding screws arranged at substantially right angles to the longitudinal axis of the socket, an insulating casing having a threaded area screwed upon the screw shell lamp contact and surrounding both the lamp terminals and the wire terminals.”
